(57) **CLAIM**

The ornamental design for an automatic injection device, as shown and described.

DESCRIPTION

FIG. 1 is a front perspective view of an automatic injection device with a removable cap off showing the design; FIG. 2 is a front elevation view thereof; FIG. 3 is a rear elevation view thereof; FIG. 4 is a left side elevation view thereof, the right side being a mirror image; FIG. 5 is a top plan view thereof; and, FIG. 6 is a bottom plan view thereof. The portions of the automatic injection device shown in broken lines form no part of the claimed design.
